RECORD ENVELOPE

Edward E. Modes, Chicago, Ill.

Application November 26, 1945, Serial No. 630,881

2 Claims. (Cl. 206—62)

1

This invention relates to an envelope for receiving a phonograph record and the like, and more particularly to such envelope having means for facilitating the quick and easy introduction of the record into the envelope.

Record envelopes as heretofore made have been so constructed as to render it difficult to introduce a phonograph record or the like thereinto, and requiring the use of both hands for opening up the sides of the open end of the envelope. This has been a difficult operation as one hand of the operator must at the same time hold the record and push it toward the interior of the envelope. This has been rendered no easier by laying the envelope on a table top or the like and then spreading the sides of the open end apart for insertion of the record, as this operation is likewise attended by confusion and difficulty. To state it another way; the operator does not have enough hands to conveniently insert a record into its envelope by the old method. By the present invention I have completely eliminated these difficulties and have rendered it simple and easy to introduce the record into the envelope.

Among the objects of my invention are: to provide a new and improved record envelope; to so construct the side walls of the open end of a record envelope that the envelope may be held in one hand and the record in the other hand and by turning the record through a slight angle it may be easily pushed into the envelope; to provide a record envelope in which the side walls of the open end are so cut out as to expose the inner face of one side wall on one side of the center line and to expose the inner face of the other side wall on the other side of the center line; to provide a short recess in the side walls of the open end of the envelope with a portion of one side wall cut out on one side of the recess and a portion of the other side wall cut out on the other side of the recess; and to cut out portions of the side walls at the open end of the envelope in non-registering positions but having only a portion of such cut-outs coinciding.

Other objects and advantages will become readily apparent from the following detailed description taken in connection with the accompanying drawings in which:

Fig. 1 is a side elevation partly broken away looking toward one side face of the envelope.

Fig. 2 is a diagrammatical side elevation showing the first step in starting the introduction of a record into the envelope.

Fig. 3 is a view similar to Fig. 2 but showing the record as rotated into the plane of the envelope to spread the sides of the envelope slightly apart.

Fig. 4 is a view similar to Fig. 3 but showing the envelope as having been inserted partway into the envelope.

2

Fig. 5 is a side elevation of a modified form of my invention.

While my invention resides in the combination, construction and arrangement of parts illustrated in the drawings, I have shown therein for illustrative purposes only, a preferred embodiment, and wish it understood that the same is susceptible of modification and change without departing from the spirit and scope of the appended claims.

In the form shown in the drawings, and referring to Figs. 1-4 as showing the preferred form, my improved envelope comprises the side faces 1 and 2 secured together in any suitable manner at the side edges 3 and 4 and the bottom edge 5. One form of fastening these side faces together is by bending these faces together along the edge 4 so that the upper edge as viewed in Fig. 1 extends somewhat beyond the adjacent edge of side face 2 and then bending the extending portion 6 downwardly over the rear side of face 2 and then gluing or otherwise securing the same thereagainst. The face 1 also has an extending edge which after the part 6 is secured to the back of face 2 is then bent over and likewise secured to the back side of face 2 as indicated at 7 in Fig. 1 to form a bottom for the envelope. The edges of the front and rear faces 1 and 2 at the right hand side of the envelope as shown in Fig. 1 are unattached from envelope edge 3 to edge 4 and constitute what I will refer to as the open edges of the open end of the envelope.

The open edge portion of the front side 1 of the envelope is cut out from its normal full length edge 8 along the lines 9, 10, 11, 12 and 13 to form a recess in said face with the longitudinally extending edge 10 of the front face 1 being positioned a slight distance below the longitudinal center line 14 as viewed in Fig. 1 and then extending along the lines 11, 12 and 13 above the center line in the form of a curve or other inclination until it merges with the top edge of the open end of the envelope at 15 as shown in full lines in Fig. 1.

45 The open edge portion of the rear face 2 is cut with a similar recess starting with the top edge 16 and then continuing inwardly along the line 17 and then following along the lines 18, 19, 20 and 21 and merging into the outer edge at 22.

50 The inwardly extending edge 17 is positioned a slight distance above the longitudinal center line 14 as viewed in Fig. 1 so that when the envelope is viewed from one of the side faces these laterally spaced longitudinal edges 10 and 17 form a groove or recess 23 into which the edge of a phonograph record or the like 24 may be inserted as shown in dotted lines in Fig. 2. The recess 9—13 formed in the front wall 1 of the envelope is reversely positioned with relation to the recess 55 17—21 formed in the rear wall of the envelope.

From this construction it will be seen that when the record 24 occupies the position shown in Fig. 2 with its edge in the groove or recess 23 a twisting movement of the record to bring it into the plane of the envelope will cause one side of the record to pass through the recess or cut-out 9-13 until it contacts the exposed face 25 of the other wall of the envelope. Likewise the opposite bottom side portion of the record will at the same time pass through the recess or cut-out portion 17-21 in the rear wall and contact the exposed face 26 of the front wall of the envelope. When the record is thus brought into a plane parallel with the plane of the envelope as seen in Fig. 3, the open edges of the envelope will be spread a slight distance apart and the record may then be pushed into the envelope as shown in Fig. 4.

In Fig. 5 I have shown a modification of my invention in which the main portion of the body of the envelope is similar to that of Fig. 1, but in which the contour of the cut-out portions are circular, or nearly circular, instead of irregular as in Fig. 1. In the form shown in Fig. 5 the cut-out portion in the front wall 1 of the envelope is indicated at the solid line 27, 28, 29 and 30, and the cut-out portion in the back wall is indicated by the dotted line 31 and 32 which merges into the solid line 33 and 34. These cut-outs are thus seen to be identical but in reverse position, that is, the cut-out in the front wall as viewed in Fig. 5 extends downwardly farther than the cut-out in the back wall to provide laterally displaced tabs 35 and 36 in the front and back walls respectively. These tabs or exposed portions 35 and 36 of Fig. 5 correspond in purpose and action to the tabs or exposed portions 25 and 26 of Fig. 1. These reversed insertion cut-outs at the top of the envelope (right hand side as viewed in Fig. 5) enable the side of the record to be placed against either one of the tabs 35 and 36 depending upon which face of the envelope is presented to the eye of the observer. Also the record may be placed in position to have its opposite bottom side edges simultaneously contact the inner face of both of tabs 35 and 36 and enable the record to be twisted slightly to spread the sides of the envelope and allow the record to be then pushed into the envelope.

In both of the forms of my invention the envelope is formed in both its front and back faces with a central opening 37 for displaying the label on a record.

From the above it is seen that I have provided an envelope for records and the like in which the envelope can be held by one hand of the operator and the record in the other hand and easily insert the record by a simple twisting action of the same. This eliminates the necessity of laying the envelope on a flat surface so as to have a free hand for spreading the open edges apart. This easy insertion of the record into the envelope is possible regardless of which face of the envelope is presented to the eye of the observer. The recess 23 of Figs. 1 to 4 and the cut out portions 28, 29 and 32, 33 of Fig. 5 provide finger openings which expose a part of the edge portion of a record and facilitate withdrawing the record from the envelope. This construction of envelope enables the economical manufacture of the envelope as the reversed cut-outs in the front and back walls may be easily made when the material of the envelope is lying flat by simply

cutting the same to shape in a cutting die and then folding and securing the three edges of the envelope together.

While I have for illustrative purposes described my invention as applied to an envelope for phonograph records, I wish it understood that this envelope may also be used for receiving other flat and more or less thin objects adapted for insertion therein in the manner described.

I claim:

1. An envelope adapted to receive a phonographic record and the like, comprising, a flat container having front and back walls closed along three edges and open along the fourth edge, the front wall having in its open edge an elongated, cut-out formed at its inner end with a substantially straight edge substantially parallel with the longitudinal center line of the envelope that extends at right angles to the open edge thereof, said straight edge being positioned to one side of the center line, said cut-out extending from said straight edge across the center line along a curved line having a radius of curvature not less than half the width of the open edge to meet said open edge adjacent the closed side edge on the opposite side of the center line from the straight edge, the back wall having a similar cut-out positioned reversely to that in the front wall, whereby the two straight edges are positioned parallel to each other and laterally spaced apart a small distance on opposite sides of said center line so that a record may be inserted at its edge between said straight edges and then rotated toward the exposed cut-outs until parallel with the envelope at which time it may readily be pushed into the envelope.

2. An envelope adapted to receive a phonographic record and the like, comprising, a flat container having front and back walls closed along three edges and open along the fourth edge, one of said walls having a cut-out formed along its open edge, said cut-out having at one end an abrupt inwardly extended edge positioned slightly beyond one side of the longitudinal center line of the envelope and extending laterally therefrom along a line having a radius of curvature of at least half the width of the open edge and joining the open end edge near a side edge of the envelope, the other wall of the envelope having a cut-out formed along its open edge, said cut-out having at one end an abrupt inwardly extended edge positioned a slight distance on the opposite side of the center line from said first abrupt edge and extending laterally therefrom along a line having a radius of curvature of at least half the width of the open edge and joining the open end edge near the other side edge of the envelope, whereby said slightly spaced apart first and second abrupt edges form a notch into which an edge of a phonograph record and the like may be inserted and turned to contact the uncut edges of the open walls to open the envelope and be moved thereto.
